REAMER LOCKING DEVICE

Eugene D. Kennedy, Houston, Tex., assignor to
 Reed Roller Bit Company, Houston, Tex., a
 corporation of Texas

Application September 22, 1941, Serial No. 411,818

3 Claims. (Cl. 255—73)

This invention relates to reamers for use in drilling wells and has for its general object to provide an improved mounting for reamer cutters on the reamer bodies.

It is highly desirable in connection with reamers that the cutters be mounted on the reamer bodies in such a manner that the cutters may be readily removed and replaced in the field.

It is a further object of this invention, therefore, to provide a means for mounting reamer cutters on the reamer bodies which means may be assembled without the use of special tools or equipment and which means will be substantially foolproof in addition to providing a substantially trouble free mounting for the reamer cutters such that the reamers can not become displaced from the body in use, and such that the reamer cutter mountings will not become damaged through strain or wear so that the cutters may be allowed to become loose from the body.

Other objects and advantages of this invention will become apparent from the following description taken in connection with the accompanying drawing wherein is set forth by way of example and illustration one embodiment of the invention.

In the drawing:

Fig. 1 shows a side elevation of a reamer constructed in accordance with this invention, the upper and lower end portions of the body being broken away.

Fig. 2 is a fragmentary vertical cross section taken along the line 2—2 of Fig. 1 and showing the details of construction of cutter mounting.

Fig. 3 shows a fragmentary side elevation on the same scale as Fig. 2 illustrating the cutter mounting arrangement.

Fig. 4 is a transverse cross section taken along the line 4—4 of Fig. 1 and showing the cutter mounting arrangement on an enlarged scale.

In the drawing the body 1 of the reamer is provided with circumferentially spaced longitudinally extending recesses 2, each adapted to receive a reamer cutter 3. These reamer cutters 3 are mounted on axles or shafts 4, the ends of which extend into auxiliary recesses 5 which communicate respectively with the opposite ends of the major recesses 2. The shafts 4 are so supported that the outer portion of each cutter 3 will project outwardly beyond the regular circular contour of the reamer body.

The auxiliary recesses 5 are provided with overhanging opposite edges 6 and are adapted to receive the blocks 7 which have laterally extending tongues 8 on their opposite edges adapted to

ride beneath the overhanging edges 6 of the recesses so as to retain the blocks 7 against radial movement from their recesses.

Each of the auxiliary recesses is also provided with a recessed bottom part 9 adjacent the major recess 2, the same being adapted to receive a bearing block 10 which is in turn held against longitudinal movement by means of a dowel pin 11.

Each of the shafts 4 has a flattened end portion 12 which faces outwardly with respect to the body so that the portion of circular outline may rest upon the block 10. Each of the blocks 7 has a transverse slot therethrough which is preferably of T-shaped cross section providing overhanging edges 13 as shown in Fig. 2. This slot is adapted to receive a wedge 13a of similar cross section having portions 14 adapted to engage beneath the overhanging edge parts 13. The bottom surface 15 of each of the wedges 13a is sloped with respect to the engaging surfaces between the parts 13 and 14 indicated at 16, so that when the wedge 13a is forced laterally through the slot in one of the blocks 7 it will form a wedging engagement between such block and the adjacent flattened surface of the shaft 4. In order that this engagement might be perfect and prevent slippage between the shaft and the block 13a, each of the blocks 13a is provided with a sharpened ridge or tooth 17 extending longitudinally thereof and adapted to engage and bite into the flattened surface of the shaft 4 as the wedge is driven home.

Each wedge is adapted to be held in place by means of a spring or key 18 which is inserted behind the wedge after it has been driven home.

In assembling the device just described the blocks 10 are first put in place with the dowels 11 holding them against slippage. The cutter 3 with the shaft 4 in place therein is then put into its recess 2 with the ends of the shafts extending into the auxiliary recesses 5 respectively and lying within the seats formed in the blocks 10.

Thereupon the blocks 7 are slipped into place longitudinally of the body until they overlie the blocks 10 and the slots therein are aligned with notches 19 formed in the body on opposite sides of each of the auxiliary recesses 5 to permit the insertion of the wedges 13a. The wedges 13a are then inserted from the left as seen in Fig. 1 and are driven home with a hammer or the like. Thereupon the keys or springs 18 are inserted into place to hold the wedges against coming out.

When it is desired to disassemble the reamer

all that is necessary is to remove the keys 18, hammer the wedges 13a out of their engagement, remove the blocks 7 and lift out the reamer cutters with their associated shafts.

From the foregoing it will be seen that a means has been provided for carrying out efficiently all of the objects and advantages sought by this invention.

Having now described my invention, I claim:

1. In a reamer, a body having a major recess therein and an auxiliary recess opening into each end of the major recess, said auxiliary recess having overhanging edges, and said body having a transverse slideway intersecting each of said auxiliary recesses, a roller cutter in said major recess, a supporting shaft extending through said cutter and having its ends disposed in said auxiliary recesses, a keeper block slideable in each of said auxiliary recesses and adapted to engage beneath said overhanging edges and to overlie said shaft ends, each keeper block having a slideway transversely thereof with overhanging edges said last mentioned slideway adapted to be aligned with said slideway in the body and being cut to provide an opening through the block to expose the shaft, and a wedge member having parts adapted to engage beneath said overhanging edges of the slideway and a surface inclined with respect to said parts to wedge against the shaft when the wedge member is forced in one direction.
2. In a reamer, a body having a major recess therein and an auxiliary recess opening into each end of the major recess, said auxiliary recesses having overhanging edges, and said body having a transverse slideway intersecting each of said auxiliary recesses, a roller cutter in said major recess, a supporting shaft extending through said cutter and having its ends disposed in said auxiliary recesses, a keeper block slideable in each of said auxiliary recesses and adapted to

engage beneath said overhanging edges and to overlie said shaft ends, each keeper block having a slideway transversely thereof with overhanging edges, said last mentioned slideway adapted to be aligned with said slideway in the body and being cut to provide an opening through the block to expose the shaft, a wedge member having parts adapted to engage beneath said overhanging edges of the slideway and a surface inclined with respect to said parts to wedge against the shaft when the wedge member is forced in one direction, and a key adapted to be inserted behind said wedge member to prevent it from being accidentally displaced.

10 3. In a reamer, a body having a major recess therein and an auxiliary recess opening into each end of the major recess, said auxiliary recesses having overhanging edges, and said body having a transverse slideway intersecting each of said auxiliary recesses, a roller cutter in said major recess, a supporting shaft extending through said cutter and having its ends disposed in said auxiliary recesses, a keeper block slideable in each of said auxiliary recesses and adapted to engage beneath said overhanging edges and to overlie said shaft ends, each keeper block having a slideway transversely thereof with overhanging edges, said last mentioned slideway adapted to be aligned with said slideway in the body and being cut to provide an opening through the block to expose the shaft, and a wedge member having parts adapted to engage beneath said overhanging edges of the slideway and a surface inclined with respect to said parts to wedge against the shaft when the wedge member is forced in one direction, said last mentioned surface having a sharpened tooth extending longitudinally thereof and adapted to bite into the surface of the shaft as the wedge is driven home.
